UNITED STATES PATENT OFFICE.

RALPH P. THOMPSON AND EMIL KOEB, OF SPRINGFIELD, OHIO.

FEED DEVICE FOR GASOLENE AND AIR FOR GAS-ENGINES.

SPECIFICATION forming part of Letters Patent No. 740,488, dated October 6, 1903.

Application filed November 11, 1901. Serial No. 81,867. (No model.)

To all whom it may concern:

Be it known that we, RALPH P. THOMPSON and EMIL KOEB, citizens of the United States, residing at Springfield, in the county of Clark and State of Ohio, have invented a certain new and useful Improvement in Feed Devices for Gasolene and Air for Gas-Engines, of which the following is a specification.

The invention relates to devices for regulating and controlling the admission of the charge of gasolene and air into the explosion-chamber of a gas-engine, and has for its objects to insure a positive and reliable operation of the valves controlling the flow of the gasolene, in conjunction with means for supplying air with the charge in sufficient quantity to insure its positive injection into the working cylinder, to improve the air-injecting pump in its construction and operation in relation to the valves controlling the admission of the gasolene, to supply outside air to the air-injecting pump to the amount required for a proper charge, to automatically operate the controlling-valves for admitting the charge of gasolene from the source of supply to the explosion-chamber through the operation of the air-injecting pump, and to improve generally the construction and operation of the devices which enter into the feed appliances as a whole; and the invention consists in the features of construction and combination of parts hereinafter described and claimed.

In the drawings, Figure 1 is a top or plan view of a gas-engine having applied thereto the air and gasolene feed appliance of the invention; Fig. 2, a side elevation of the same, showing the air-injecting pump with its piston in its receded position; Fig. 3, a similar view to Fig. 2, showing the air-injecting pump with its piston advanced; Fig. 4, a detail, being a top plan view of the parts shown, with a portion of the air-injecting pump in section; Fig. 5, a detail in section on line xx of Fig. 4, and Fig. 6 a detail in section on line yy of Fig. 4.

The invention relates specifically to the feeding of the gasolene and air into the explosion-chamber, and only so much of a complete engine is shown in the drawings as is deemed necessary to properly illustrate the construction, location, arrangement, and op-

eration of the devices to which the invention properly pertains; nor is it deemed necessary to specifically describe each and every part or element shown in the drawings, and the detail description, therefore, will be confined to the parts or elements of the invention.

The engine shown is of the ordinary class of two-piston gas-engines, the engine having a cylinder A, with a neck A' and an extension A² at opposite ends of the main cylinder, in which cylinder and its neck and extension the power-pistons are located and operate, and, as shown, holes a^2 are provided at each end of the main cylinder for lubricating the power-pistons. The upper side of the cylinder in the construction shown has therein an opening a in communication with the explosion-chamber, and this opening is surrounded by a wall or ledge a' , having a flat face. A plate B is mounted on the flat face of the wall or ledge and secured in place by bolts b or otherwise, and on this plate is mounted a second plate or head C, secured in place on the plate B by bolts c or otherwise. The plate or head C in the construction shown has a depending circular boss or plug C', which is entered into a hole therefor in the plate B, and in this plug is a chamber c' , which, as shown, extends slightly into the body of the plate or head. The plate or head has on its upper face extending up therefrom a boss or nipple C², having in its end a hole c^2 and provided with an exterior screw-thread around its end to receive a cap or cover C³, which has therein a hole to align with the hole c^2 in the boss or nipple. A casing or shell D, having therein a chamber d and a chamber d', separated one from the other by a cross partition or wall d², is screw-threaded, as shown, onto a boss or nipple D', which in turn is screw-threaded into the plate or head C, so as to leave between the end of the boss or nipple and the face of the opening into which it is screw-threaded a chamber c⁴, which is in communication with the chamber c' by a duct or passage c^4 , and the end of the boss or nipple D' has therein a chamber d³, which is in communication with the chamber d' by a passage d⁴ in the boss or nipple. A screw-threaded valve-stem E operates in the neck of the shell D, and the stem is encircled by a

cap-nut D², having a chamber therein to receive a packing d², by which a tight joint is provided around the valve-stem. The inner end of the stem E has a point e, which fits 5 into a port or opening e' in the cross-wall d², so that by turning the stem in the proper direction the port or opening can be closed or opened, and to turn the stem a hand-wheel E² is attached to the outer end thereof. The 10 boss or nipple D' carries a valve-stem F, on the lower end of which is a valve-disk f, which controls a port or opening f' between the chamber c³ and the chamber d³, so that when the valve-disk is open and the valve E is like- 15 wise open communication is established between the chamber d³ and the chamber c³ for the connected chambers to form, in effect, a passage in the shell or casing and the boss or nipple into the head or plate, which passage 20 consists of an upper section formed by the chamber d, an intermediate section formed by the chamber d', and a lower section formed by the chamber d³, which last-named chamber opens into the chamber c³, which chamber c³ 25 is a supply-chamber into which the gasolene is delivered and from which the gasolene is supplied to the chamber c' to be therein commingled with air for a mixture of gasolene and air for the explosive charge. The opposite 30 end of the stem F to the valve-disk has thereon a nut f², and encircling the stem between the nut f² and the end face of the boss or nipple D' is a coil-spring f³, by means of which the valve-disk is held normally seated to close 35 the port or opening into the chamber c³, so that gasolene cannot enter such chamber. A valve-stem G is carried by the plate or head C and the boss or nipple C², and this stem at one end has attached thereto a valve-disk g, which 40 seats against a face around a port or opening g' at the discharge end of the chamber c', by means of which stem and valve-disk the discharge from the chamber c' of the charge of gasolene and air is controlled. The stem G 45 at the end opposite to the valve-disk has thereon an adjustable nut g², and encircling the stem between the nut and the end face of the chamber c' is a coil-spring g³, by means of which the valve-disk is held normally 50 seated, closing the port or opening from the chamber c' and preventing the escape of the contents of such chamber.

A tubular stem I, having an opening or passage i, extends out from one side of the 55 plate or head C and receives on its end a coupling-nut i' for a coupling-tube I', which is screw-threaded into the eduction or discharge nipple j of the air-injecting pump, the discharge-passage j' of which communicates 60 with the passage i, which passage is continuous through the tubular stem, the coupling-nut, and tube and discharges into the receiving-chamber c', as shown in Fig. 6. The air-injecting pump has a cylinder J of the proper 65 length and diameter, in which is located and operates a piston K, connected to a piston-rod K' by an eye k' on the piston-rod and a

pivot-pin k in the piston, so that the outer or free end of the rod is free to rise and fall, in the construction shown, with the reciprocation of the piston. The discharge end of the cylinder J is closed by a cap or cover J', screw-threaded onto the end of the cylinder, and this cap has screw-threaded thereinto a plug L, having an axial passage or chamber 70 l', into which ports or openings l² lead through the body of the plug, and extending out from the plug is a tubular stem L', which carries a valve-stem M, having at one end a valve-disk m, which seats against a face around a port or opening l at the discharge end of the chamber or passage l' into the cylinder in front of the cap or head and between the cap or head and the piston, so that with the advance stroke of the piston the valve-disk will be opened, admitting air into the chamber of the cylinder 80 between the piston and cylinder-head for the return stroke of the piston to force the air out through the eduction or discharge and the passage i into the receiving-chamber for 85 the gasolene and air. The tubular stem L' is encircled by a coil-spring m', one end of which abuts against the end face of the plug L and the other end of which contacts a cross-pin m² for the spring to act and close 90 the valve-disk m after each opening thereof and holding the disk closed normally. The valve-disk m when opened allows air to pass through the ports or openings l² into the chamber or passage l' and discharge through 95 the opening or port l into the chamber of the injecting-pump in front of the pump-piston, and the air drawn into the chamber of the injecting-pump and forced therefrom into the receiving-chamber c' commingles with 100 the gasolene in said chamber and serves to bring the gasolene up to full vaporization, which is a requisite before admitting the charge into the explosion-chamber of the 105 engine in order to increase the efficiency of the charge, attain the proper mixture and vapors, produce the best results, and secure the highest effects from the explosion thereof in the 110 explosion-chamber of the engine.

A cross-head N is connected to one piston 115 of the engine, and a cross-head N' is connected to the other piston of the engine, and from the cross-head N, at each end thereof, a connecting-rod O extends to a crank P of a crank-shaft Q, and from the cross-head N', 120 at each end thereof, a connecting-rod O' extends to a crank P' of the crank-shaft Q, which shaft is to be mounted in suitable journal-boxes. (Not shown.) An arm R extends up from the cross-head N' in line with 125 the center of the cylinder J in the construction shown, and the piston-rod K' is attached to the outer end of this arm R by a coupling or fork head o and a pivot-pin o', so that with the reciprocating movement of the cross-head the arm R will be carried back and forth, giving a reciprocating movement to the piston K from the piston-rod K', which 130 movement of the piston is straight, by reason

of the pivotal connection between the piston and its rod, which allows of the movement of the piston-rod coincident with the movement of the operating-arm R from the movement of the cross-head N', which carries the arm. The cylinder J in the construction shown is mounted on the cylinder of the engine so as to have an upward inclination at its outer or open end, and, as shown, the cap or head of the cylinder has a band p and the cylinder has a band p' , each band having ears p^2 , which receive the edge of a plate q , attached to the engine-cylinder, through which plate and ears bolts q' pass, mounting the cylinder J firmly in position. The neck A' has formed therewith or connected thereto a shell or casing S, in which is a piston T, connected with a piston of the engine, and these parts constitute an air-pump for supplying air to the explosion-chamber between the two pistons of the engine through a conducting-pipe U, and, as shown, an opening n on each side is formed in the neck A' and the shell or casing S for the traverse of the cross-head N, and an opening n' is formed on each side in the extension A² for the traverse of the cross-head N', and the opening n extends forward of the limit of recession of the piston T, so as to escape air during a portion of the advance of the piston. The air-pump formed by the shell or casing and the piston in connection with the escape-openings n are not herein specifically described, as they constitute the subject-matter of another application, the same being application Serial No. 81,642, filed November 8, 1901.

The operation is as follows: The gasoline from the source of supply flows through the pipe H into the chamber or first section d of the feed-passage for the gasoline. The stem E is turned as required to raise the needle-valve or point e from its seat around the port or passage e' , so as to leave a sufficient space for the gasoline to flow from the chamber or first section d into the chamber or second section d' of the passage for the gasoline, and from the chamber or second section d' of the passage the gasoline flows through the duct or passage d^2 into the last chamber or section d^3 of the gasoline-passage, where it is retained until the valve-disk f is opened, allowing the proper amount thereof to enter the chamber c^3 and pass from such chamber through the duct or passage c^4 into the receiving and mixing chamber c' for the gasoline and air. The air to bring the charge up to the pressure of a full atmosphere is forced or inducted into the receiving and mixing chamber c' through the passage i from the air-injecting pump, completing the charge of mixed gasoline and air for admission into the explosion-chamber of the gas-engine, which admission occurs with the opening of the valve-disk g as the air is forced into the receiving and mixing chamber. The valve-stem E when adjusted for the proper opening of its needle or pointed end e can be left in that position for ordinary

use, but can be readily turned to increase or decrease the space between the needle or pointed end of the stem and the seat therefor on the face of the port or passage controlled by the needle-valve or pointed end, as circumstances may require. The valve-disk f is held normally closed by the spring f^3 and is opened by the suction of the outward traverse or advance stroke of the piston of the air-injecting pump, allowing the gasoline to enter the chamber c^3 and flow through the duct or passage c^4 into the receiving-chamber c' , the valve-disk g of which is held normally closed by the spring g^3 and is firmly seated by the suction from the outward travel or advance stroke of the piston of the air-injecting pump, so that the gasoline entering the receiving and mixing chamber will be retained therein during the return stroke or travel of the piston. The outward traverse or advance stroke of the piston of the air-injecting-pump by its suction opens the valve-disk m for air to enter the chamber of the cylinder J between the head of the cylinder and the piston, so that with the outward traverse or advance stroke of the piston of the air-injecting-pump gasoline flows into the receiving and mixing chamber c' and air flows into the chamber of the cylinder J in front of the piston and into the receiving and mixing chamber through the passage i , giving the required charge of air and gasoline. The inward travel or receding stroke of the piston or plunger of the air-injecting pump forces the air from the education or discharge of the cylinder under pressure through the passage i into the receiving and mixing chamber c' , and the pressure opens the valve-disk g for the discharge of the air and gasoline through the port or opening of the chamber into the explosion-chamber, and with such opening of the valve-disk g the valve-disk f , which has been closed by the action of the spring f^3 at the terminus of the outward traverse or advance stroke of the piston K, is held firmly to its seat around the port f' , shutting off the flow of gasoline into the receiving and mixing chamber. The valve-disk g will be held open and the valve-disk f will be held closed during the inward traverse or return stroke of the piston K, preventing the gasoline from flowing into the receiving and mixing chamber from the gasoline-passage and allowing the charge of gasoline and air to be forced out through the open disk valve g into the explosion-chamber. Each outward traverse or advance stroke of the plunger K opens the induction-valve f , with the education-valve g closed, for the admission and retention of the charge of gasoline in the chamber c' , and each inward traverse return stroke of the piston K opens the education-valve g , with the induction-valve f closed, for discharging the contents of the receiving and mixing chamber into the explosion-chamber, and these movements of the respective valves will continue as long as the

engine runs, thus insuring an automatic opening and closing of the respective valves at the time required for admitting the gasoline and for discharging the gasoline and air, thus insuring an automatic feed for gasoline and air to the explosion-chamber as long as the engine operates.

The arrangement shown opens the induction-valve *f* with the eduction-valve *g* closed as the engine-pistons travel outward or in the advanced direction for the production of power, so that the feed of the gasoline into the receiving and mixing chamber occurs after the explosion and during the period of the time occupied in the travel of the power-pistons outward or in their advanced direction, at the end of which time the explosion-chamber is cleared of the gases, vapors, and products of the explosion. The eduction-valve *g* is opened to discharge from the receiving and mixing chamber the charge with the inward or receding movement or stroke of the piston *K*, with the induction-valve *f* closed, shutting off the admission of gasoline to the receiving and mixing chamber during the return or receding stroke of the piston, forcing the prepared charge into the explosion-chamber. It will thus be seen that the opening and closing of the induction and eduction valves for the feed is in correlation with the strokes of the power-pistons, the gasoline-feed being open with the eduction closed as the power-piston makes its advance or outward movement and the gasoline-feed being cut off and the eduction open as the power-piston makes its return or inward movement. The valve-stem carrying the needle valve or point enables the feed of the gasoline to be accurately and correctly regulated, and the induction-valve for the gasoline-passage actuated by suction from the movements of the air-injecting piston, the stroke of which is requisite for the feed of gasoline required for a charge, places the control of the feed automatically from the movements of the air-injecting piston, which piston also automatically opens the eduction-valve for the charge of gasoline and air, so that the opening and closing of the induction gasoline-valve and the eduction charging-valve are both automatically performed by the movements of the piston of the air-injecting pump, thus placing the control of the gasoline and air under the movements of the piston of the air-injecting pump. The appliance is simple in construction and automatic in operation, depending for its operation on the running of the engine, and in use the appliance operates to perfectly and accurately control and regulate the feed of the gasoline, the charging with air, and the discharge of the mingled gasoline and air into the explosion-chamber, thus insuring in each instance a perfectly uniform and regulated feed and discharge of gasoline and air.

We claim—

1. In a gasoline and air feed for gas-engines, the combination of a gasoline-passage com-

prising an upper section, an intermediate section and a lower section, a partition between the upper and intermediate sections and having a port therein, a regulating-valve controlling the flow through the port, a feed duct or passage between the intermediate section and the lower section, a supply-chamber below and in communication with the lower section of the gasoline-passage, a pressure-actuated valve controlling the discharge from the lower section of the gasoline-passage into the supply-chamber, a receiving and mixing chamber in communication with the supply-chamber, and a pressure-actuated valve controlling the discharge from the receiving and mixing chamber and opening with the closing of the discharge-valve for the supply-chamber and closing with the opening of the discharge-valve for the supply-chamber, substantially as described.

2. In a gasoline and air feed for gas-engines, the combination of a gasoline-passage comprising an upper section, an intermediate section and a lower section, a partition between the upper and intermediate sections and having a port therein, a regulating-valve controlling the flow through the port, a feed duct or passage between the intermediate section and the lower section, a supply-chamber below and in communication with the lower section of the gasoline-passage, a pressure-actuated valve controlling the discharge from the lower section of the gasoline-passage into the supply-chamber, a receiving and mixing chamber in communication with the supply-chamber, a pressure-actuated valve controlling the discharge from the receiving and mixing chamber and opening with the closing of the discharge-valve for the supply-chamber and closing with the opening of the discharge-valve for the supply-chamber, an air-injecting pump, and an air-passage leading into the receiving and mixing chamber from the chamber of the injecting-pump to supply air to the receiving and mixing chamber and by its operation open and close the discharge-valves of the gasoline-supply chamber and the receiving and mixing chamber, substantially as described.

3. In a gasoline and air feed for gas-engines, the combination of a gasoline-passage comprising an upper section, an intermediate section and a lower section, a partition between the upper and intermediate sections and having a port therein, a regulating-needle or pointed valve controlling the flow of gasoline through the port, a feed duct or passage between the intermediate section and the lower section of the gasoline-passage, a supply-chamber below and in communication with the lower section of the gasoline-passage, a valve actuated by suction to open and spring-actuated to close for controlling the discharge from the lower section of the gasoline-passage into the supply-chamber, a receiving and mixing chamber in communication with the supply-chamber, a valve actuated by pressure

to open and spring-actuated to close for controlling the discharge from the receiving and mixing chamber, said valve opening with the closing of the discharge-valve for the supply-chamber and closing with the opening of the discharge-valve for the supply-chamber, substantially as described.

4. In a gasoline and air feed for gas-engines, the combination of a gasoline-passage comprising an upper section, an intermediate section and a lower section, a partition between the upper and intermediate sections and having a port therein, a regulating-needle or pointed valve controlling the flow of gasoline through the port, a feed duct or passage between the intermediate section and the lower section of the gasoline-passage, a supply-chamber below and in communication with the lower section of the gasoline-passage, a valve actuated by suction to open and spring-actuated to close for controlling the discharge from the lower section of the gasoline-passage into the supply-chamber, a receiving and mixing chamber in communication with the supply-chamber, a valve actuated by pressure to open and spring-actuated to close for controlling the discharge from the receiving and mixing chamber, said valve opening with the closing of the discharge-valve for the supply-chamber and closing with the opening of the discharge-valve for the supply-chamber and closing with the opening of the discharge-valve for the supply-chamber, an air-injecting pump, an air-passage leading into the receiving and mixing chamber from the chamber of the injecting-pump for the pump to supply air to the receiving and mixing chamber and have the suction of the pump open the discharge-valve from the supply-chamber and the pressure of the pump open the discharge-valve from the receiving and mixing chamber, substantially as described.

5. In a gasoline and air feed for gas-engines, the combination of a plate or head having a receiving and mixing chamber, a valve controlling the discharge from the receiving and mixing chamber, an entering-chamber for gasoline in the plate or head, a passage between the entering-chamber and the receiving and mixing chamber, a shell or casing on the plate or head, a partition dividing the interior of the shell or casing into two chambers or compartments, a port or passage in the partition, a needle or pointed valve controlling the port in the partition, a boss or nipple having the shell or casing attached thereto, a chamber in the boss or nipple, a passage connecting the chamber of the boss or nipple with a chamber of the shell or casing, a valve controlling the communication between the chamber of the boss or nipple and the entering-chamber of the plate or head, an air-passage leading into the receiving and mixing chamber, and an air-injecting pump in communication with the receiving and mixing chamber for forcing air into the chamber.

6. In a gasoline and air feed for gas-engines, the combination of a gasoline-passage com-

prising an upper section, an intermediate section and a lower section, a partition between the upper and intermediate sections and having a port therein, a regulating-needle or pointed valve controlling the flow of gasoline through the port, a feed duct or passage between the intermediate section and the lower section of the gasoline-passage, a supply-chamber below and in communication with the lower section of the gasoline-passage, a valve actuated by suction to open and spring-actuated to close for controlling the discharge from the lower section of the gasoline-passage into the supply-chamber, a receiving and mixing chamber in communication with the supply-chamber, a valve actuated by pressure to open and spring-actuated to close for controlling the discharge from the receiving and mixing chamber, said valve opening with the closing of the discharge-valve for the supply-chamber and closing with the opening of the discharge-valve for the supply-chamber, an air-injecting pump, an air-passage leading into the receiving and mixing chamber from the chamber of the injecting-pump for the pump to supply air to the receiving and mixing chamber and have the suction of the pump open the discharge-valve from the supply-chamber and the pressure of the pump open the discharge-valve from the receiving and mixing chamber, a passage leading from the external air into the air-injecting pump, and a valve controlling the admission of air from the passage into the chamber of the air-injecting pump, said valve actuated by the suction of the injecting-pump to open and spring-actuated to close the passage, substantially as described.

7. In a gasoline and air feed for gas-engines, the combination of a gasoline-passage comprising an upper section, an intermediate section and a lower section, a partition between the upper and intermediate sections and having a port therein, a regulating-needle or pointed valve controlling the flow of gasoline through the port, a feed duct or passage between the intermediate section and the lower section of the gasoline-passage, a supply-chamber below and in communication with the lower section of the gasoline-passage, a valve actuated by suction to open and spring-actuated to close for controlling the discharge from the lower section of the gasoline-passage into the supply-chamber, a receiving and mixing chamber in communication with the supply-chamber, a valve actuated by pressure to open and spring-actuated to close for controlling the discharge from the receiving and mixing chamber, said valve opening with the closing of the discharge-valve for the supply-chamber and closing with the opening of the discharge-valve for the supply-chamber, an air-injecting pump, an air-passage leading into the receiving and mixing chamber from the chamber of the injecting-pump for the pump to supply air to the receiving and mixing chamber and have the

suction of the pump open the discharge-valve from the supply-chamber and the pressure of the pump open the discharge-valve from the receiving and mixing chamber, a plug entered into the cylinder-head of the pump, a chamber in the plug, passages leading from the chamber in the plug to the external air, and a valve controlling the discharge from the chamber of the plug actuated by the suction of the pump to open and spring-actuated to close, substantially as described.

8. In a gasoline and air feed for engines, the combination of a plate or head attached to the cylinder of the engine and having a receiving and mixing chamber therein, a valve controlling the discharge from the receiving and mixing chamber into the engine-cylinder, said valve actuated by pressure to open and spring-actuated to close, a gasoline-passage comprising an upper section, an intermediate section and a lower section, a partition between the upper and intermediate sections and having a port therein, a regulating-needle or pointed valve controlling the flow of the gasoline through the port, a feed duct or passage between the intermediate section and the lower section of the gasoline-passage, a supply-chamber below and in communication with the lower section of the gasoline-passage, a valve controlling the discharge from the lower section of the gasoline-passage into the supply-chamber, said valve actuated by suction to open and spring-actuated to close, a duct furnishing communication between the supply-chamber and the receiving and mixing chamber, an air-injecting pump mounted on the cylinder of the engine and having communication with the receiving and mixing chamber and operating by its suction to open the valve of the supply-chamber and by its pressure to open the valve of the receiving and mixing chamber, one valve opening with the other valve closed, a plug entered into the cylinder-head of the pump, a chamber in the plug, passages leading from the chamber to the external air through the plug, and a valve controlling the chamber in the plug actuated by the suction of the pump to open and spring-actuated to close, substantially as described.

9. In a gasoline and air feed for engines, 45 the combination of a plate or head attached to the cylinder of the engine and having a receiving and mixing chamber therein, a valve controlling the discharge from the receiving and mixing chamber into the engine-cylinder, 50 said valve actuated by pressure to open and spring-actuated to close, a gasoline-passage comprising an upper section, an intermediate section and a lower section, a partition between the upper and intermediate sections 55 and having a port therein, a regulating-needle or pointed valve controlling the flow of the gasoline through the port, a feed duct or passage between the intermediate section and the lower section of the gasoline-passage, a supply-chamber below and in communication with the lower section of the gasoline-passage, a valve controlling the discharge from the lower section of the gasoline-passage into the supply-chamber, said 60 valve actuated by suction to open and spring-actuated to close, a duct furnishing communication between the supply-chamber and the receiving and mixing chamber, an air-injecting pump mounted on the cylinder of 65 the engine and having communication with the receiving and mixing chamber and operating by its suction to open the valve of the supply-chamber and by its pressure to open the valve of the receiving and mixing chamber, one valve opening with the other valve closed, a plug entered into the cylinder-head of the pump, a chamber in the plug, passages leading from the chamber to the external air through the plug, and a valve controlling the chamber in the plug actuated by the suction of the pump to open and spring-actuated to close, substantially as described.
